Pa., assignor to United Research Corporation,
Long Island City, N. Y., a corporation of Delaware

Application November 30, 1931, Serial No. 578,016

4 Claims. (Cl. 250—27.5)

This invention relates to photo-electric tubes, and particularly to multiple element photo-tubes.

Difficulty has been experienced in getting satisfactory response from photo-tubes to fluctuating light beams having fluctuation frequencies varying over the entire audible frequency range.

An object of this invention is to combine a plurality of photo-responsive elements in a single photo-tube structure in which the various elements are respectively more sensitive to different ranges of the audible sound spectrum.

Another object of this invention is to combine in a photo-tube a plurality of separately photo-responsive elements.

Still another object is to combine in a photo-tube separate photo-responsive elements of different photo-responsive materials.

A further object of this invention is to combine a photo-tube with a record system in which the recorded frequencies are subdivided into groups or ranges of frequencies, and the photo-tube is adapted to respond to the groups of frequencies through separate responsive elements.

A still further object of this invention is to incorporate into a photo-tube a plurality of photo-responsive materials.

Still a further object of this invention is to utilize a plurality of photo-responsive alkaline metals, including potassium, sodium, caesium, lithium and other members of the alkali and alkaline earth metal groups.

Previously constructed photo-tubes have customarily utilized but a single photo-sensitive material, usually potassium or potassium hydride upon suitable electrodes within an evacuated container.

It is found that the various alkali, and alkaline earth metals are differently responsive to light fluctuations within different frequency ranges.

This invention provides a photo-tube and record system in which the photo-tube has a plurality of cathodes respectively composed of different photo-responsive metals, such as potassium, sodium, lithium, caesium, etc., which are adapted to be connected in a single circuit or in separate circuits, and may be separately responsive to separate frequency records. The record may desirably consist of a plurality of tracks in separate frequency ranges upon a single film, the separate record tracks respectively cooperating with the separate cathodes in the single tube.

This invention thus provides a new and useful photo-tube construction, adapted to cooperate with a multiple-track record for the production

of a superior and improved sound transcription.

Other objects and structural details of the invention will be apparent from the following description when read in connection with the accompanying drawing in which:

Fig. 1 is a top view of a photo-tube and record embodying this invention.

Fig. 2 is a front view of the same embodiment, and

Fig. 3 is a side view of the same embodiment.

Referring to the drawing, an evacuated container 1 is provided having a plurality of cathode electrodes 2, 3, and 4, and a single filamentary anode 5.

The anode 5 is desirably supported by lead wires 6 and 7 passing through a press to contact-prongs carried in a base 8 as shown. The cathode 2 may be carried upon a lead wire 9, the cathode 3 upon a lead wire 10, and the cathode 4 upon lead wire 11, all of which likewise pass through the press to prongs in the base 8 as shown.

Shield members 12 and 13 of insulating material are positioned between the respective cathodes 2, 3 and 4 and may be supported therefrom, or may be supported in any other convenient way.

Alternatively, the shields may of course be positioned outside of the tube, and so arranged as to separate the beams of light to the respective cathodes.

In constructing the photo-tube of this invention, the press and lead wires may be prepared in the usual way, with the cathode supports and anode attached to the lead wires. The respective cathodes may then be prepared by applying the appropriate alkali or alkaline earth metal in the form of a coating upon the supports. This is preferably done under non-oxidizing conditions, as under a blanket of nitrogen or carbon dioxide or in a vacuum, by methods which are well known to those skilled in the art. After application of the photo-responsive metals to the cathode support structures, the mount with cathodes and anodes may be sealed into the container 1, which is thereafter evacuated by well known methods, which may include appropriate baking out steps. However, care must be taken that any heating processes applied to the structure cause as little volatilization of the respective photo-sensitive metals as possible, in order to avoid mixing the metals upon their respective cathode supports. After the evacuation, the customary small quantities of hydrogen, rare gases or mixtures of gases may be added in the usual way, with the usual

sensitizing treatment, care being taken as before that a minimum heating is given, to minimize volatilization of the respective metals.

The tube as thus constructed and prepared may then be based and mounted upon an appropriate tube socket in operative relationship with the film record 14 as shown in the drawing, and appropriately connected through the socket contacts to the usual output circuits, or to the obvious modifications thereof.

The film record 14 may have three sound tracks 15, 16 and 17 thereon as shown, and an appropriate optical system may be provided for projecting light through the sound tracks on to the respective photo-tube members in the usual way. The optical system may provide a long light bar covering all three sound records, in the usual manner, or three separate optical systems respectively cooperating with the three records and the cathodes may be provided. The members 12 and 13 then serve to prevent light from one record overlapping on to other cathodes than the one directly before the record. The tracks upon the record strip 14 may desirably comprise separate ranges of the audible frequency range, or frequency spectrum. For instance, the record 15 may contain the frequencies in the lower third of the audible range, the record 16 may contain the middle third, and the record 17 the top third. For the purpose of dividing the audible vibration range into such portions the audible frequency vibration members may be used, or the frequency range may be divided in terms of octave, one range covering one-third of the number of effec-

tive octaves, and the other two respectively the remaining thirds of the octaves.

By this invention there is thus provided a new and useful photo-tube.

While there is here disclosed but a single embodiment of the inventive concept, it is possible to produce still further embodiments without departure from the spirit of the invention, and it is, therefore, desired that only such limitation shall be imposed upon the appended claims as are stated therein or required by the prior art.

The invention claimed is:

1. A photo-tube comprising a plurality of spaced photosensitive electrodes respectively comprising different photosensitive metals, light shields of insulating material respectively positioned between said electrodes and a cooperating electrode extending parallel to said plurality of electrodes.

2. A photo-electric tube comprising a plurality of photo-sensitive electrodes respectively comprising different alkali metals, and a single co-operating non-photosensitive electrode.

3. A photo-electric tube comprising a plurality of photosensitive electrodes respectively comprising sodium, potassium and caesium, and a single cooperating non-photosensitive electrode.

4. A photo-electric tube comprising a plurality of sets of electrode surfaces, one electrode surface of each set being photosensitive, said photo-sensitive surfaces being responsive to different frequency ranges respectively.

JANET F. LAW,
Administratrix for Duff C. Law, Deceased.
